Attorney.

UNITED STATES PATENT OFFICE.

CONRAD FERRETTIE, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA.

DESIGN FOR AN OVERTSHOE.

Application filed May 25, 1929. Serial No. 31,404. Term of patent 14 years.

To all whom it may concern:

I, CONRAD FERRETTIE, a citizen of the United States, residing in Mishawaka, county of St. Joseph, and State of Indiana, have invented a new, original, and ornamental Design for an Overshoe, of which the following is a specification, reference being had to the accompanying drawing, forming a part thereof.

Fig. 1 is a side view of the overshoe showing my new design, and

Fig. 2 is a top view thereof.

I claim:

The ornamental design for an overshoe as shown.

CONRAD FERRETTIE.
